PAGE 3

Fig. 5

FIG. 6.

FIG. 7.

Figure 1 is a perspective view, taken from a forward position and from the top and one side, of an airplane embodying my new design;

Figure 2 is a top plan view of the airplane;
Figure 3 is a front elevation of the same;
Figure 4 is a bottom plan of the airplane;
Figure 5 is a side elevation of the same;
Figure 6 is an enlarged, fragmentary, top, plan view of a portion of the port wing showing an engine and pylon by which it is mounted to the wing; and

Figure 7 is a side elevation view of the engine and pylon shown in Figure 6.

The dominant features of the design reside in the portions shown in full lines.

I claim:

The ornamental design for an airplane, substantially as shown and described.
